Application August 19, 1953, Serial No. 375,110

3 Claims. (Cl. 208—165)

This invention relates to processes for the conversion of hydrocarbon material by contact with a granular contact material and more particularly to a method for introduction of granular contact material into a hydrocarbon conversion zone.

In hydrocarbon conversion systems of the moving bed type, it is customary to gravitate the granular contact material, e. g. cracking catalyst, as a compact mass from a supply hopper through a confined elongated zone known as the seal leg and thence into the hydrocarbon conversion zone. The latter is generally maintained at a higher pressure than that in the supply hopper and the length of the seal leg must be sufficiently great to provide a vertical head of catalyst in the seal leg to overcome this pressure differential.

Since the hydrocarbon conversion zone is generally maintained at a relatively high pressure, there is a tendency for hydrocarbon vapors to pass upwardly from the hydrocarbon conversion zone through the seal leg. In order to prevent excessive escape of hydrocarbon vapors in this manner, it is customary to introduce a sealing gas, for example, steam, into a sealing zone above the hydrocarbon conversion zone and adjacent the lower end of the seal leg. The sealing gas passes upwardly through the seal leg and prevents the hydrocarbon vapors from passing upwardly out of the hydrocarbon conversion zone to an excessive extent.

In using steam as a sealing gas in a process employing a granular catalyst, for example a clay catalyst, which has substantial ability to adsorb steam at the temperatures commonly employed, a problem arises since the sealing steam tends to become adsorbed by the catalyst and to be unable, therefore, to effectively perform its function of maintaining the desired pressure gradient across the seal leg. It is important for proper operation that a uniform decrease in pressure be maintained as the steam passes upwardly through the seal leg. In prior art operation, however, this has not been obtained since, as the steam enters the bottom of the seal leg, substantial amounts thereof become adsorbed on the catalyst with the result that the pressure at levels higher in the seal leg is disadvantageously low and a large pressure gradient occurs near the bottom of the seal leg. This large pressure gradient causes a danger of interference with or stoppage of the flow of catalyst through the seal leg.

Previously attempts have been made to overcome this problem by hydrating the catalyst before it enters the seal leg, for example by introducing steam into the hopper from which the seal leg receives the catalyst. This method has not been completely successful, however, since it is difficult to obtain good enough distribution of steam throughout the catalyst in the hopper to obtain complete saturation with steam and also because, even if substantially complete saturation is obtained in the hopper, a large pressure gradient still occurs at the bottom of the seal leg.

According to the present invention, the disadvantages

2

of prior art operation are overcome by introducing steam into the seal leg itself at a level intermediate of the ends of the seal leg. It has been found that such operation eliminates any excessive pressure gradient at the bottom of the seal leg.

The introduction of steam into the seal leg itself serves to maintain the contact material more nearly saturated with steam during its passage through the seal leg. Since the pressure increases as the catalyst flows downwardly through the seal leg, the amount of steam which the catalyst is capable of adsorbing increases as the catalyst flows downwardly. Therefore, unless steam is introduced into the seal leg, catalyst which is completely saturated at the top of the seal leg will be capable of adsorbing considerably more steam at the bottom of the seal leg where the pressure is substantially higher; and such adsorption of steam at the bottom of the seal leg causes a large pressure gradient. The present invention provides catalyst which is more nearly saturated with steam at the bottom of the seal leg so that excessive adsorption of sealing steam does not occur.

According to the present invention, steam can be introduced at one or more vertical levels between the ends of the seal leg. Generally the greater the number of points of introduction of steam, the more uniform will be the degree of saturation of the catalyst as it flows downwardly through the seal leg. By maintaining a more uniform degree of saturation the advantageous result is obtained of maintaining a more uniform rate of pressure increase as the catalyst moves downwardly through the seal leg, since the steam which passes upwardly from the sealing zone through the seal leg is substantially all employed in the creation of a pressure gradient rather than being adsorbed in part by the catalyst.

The invention will be further described with reference to the attached drawing which is a schematic representation of apparatus in which the process of the invention may be performed. In the drawing there are shown a hydrocarbon conversion vessel or reactor 10, a regeneration vessel 11, elevating means 12 for conveying solids after removal from the regenerator 11 upwardly to a level above the hopper 13 which is situated above reactor 10. A seal leg 14 extends downwardly from hopper 13 to reactor 10.

In operation granular solids are gravitated downwardly through the hydrocarbon conversion zone 15 within reactor 10 and are contacted therein with hydrocarbon materials introduced through means not shown to effect conversion thereof. The catalyst is then gravitated through line 16 into regenerator 11 through which it gravitates as a compact mass. In regenerator 11, the catalyst is contacted with combustion supporting gas introduced through means not shown in order to effect combustion of the carbonaceous materials contained on the catalyst, such materials having been deposited thereon during the preceding hydrocarbon conversion operation. The catalyst is then gravitated through line 17 into the elevating means 12 which may be of any suitable type, for example a bucket elevator or a pneumatic elevator of known type. From the upper end of elevating means 12 the catalyst is introduced into conduit 18 and passed therethrough into hopper 13.

The catalyst in hopper 13 is at an elevated temperature, for example about 700° F., and as originally introduced thereto is in a substantially dehydrated condition, having become dehydrated in the regenerator because of the high temperature and low partial pressure of steam therein. In order to hydrate the catalyst, steam is introduced into hopper 13 through line 19. The hydrated catalyst is withdrawn from hopper 13 through line 14 and travels through the latter as a compact mass.

The pressure in hopper 13 is relatively low, for example atmospheric pressure, whereas the pressure in the sealing zone 20 into which seal leg 14 discharges is relatively high, for example 10 p. s. i. g. In order to maintain the catalyst substantially saturated with steam during its passage through seal leg 14, steam is introduced into the latter through lines 21 and 22. The steam thus introduced becomes adsorbed on the catalyst and satisfies the increased capacity of the catalyst for steam as it travels downwardly through seal leg 14 at gradually increasing pressure.

Sealing steam is introduced into sealing zone 20 through line 23. This steam maintains sealing zone 20 at a somewhat higher pressure than the pressure in hydrocarbon conversion zone 15, thereby preventing substantial passage of hydrocarbon vapors upwardly from hydrocarbon conversion zone 15 into sealing zone 20. Part of the sealing steam passes upwardly from sealing zone 20 through seal leg 14 into hopper 13. Since the catalyst is maintained substantially saturated with steam throughout its passage through seal leg 14, the sealing steam is enabled to maintain a substantially uniform pressure gradient across the seal leg 14.

In contrast to the operation described above, an operation wherein steam is not introduced through lines 21 and 22 is incapable of providing a uniform pressure gradient across the seal leg 14. The sealing steam in such operation as it enters the lower end of seal leg 14 comes in contact with catalyst which is not saturated with steam and substantial amounts of the sealing steam become adsorbed on the catalyst at that point. Thus there is a large decrease in pressure of the sealing steam near the lower end of the seal leg whereas in the operation described according to the invention the sealing steam decreases in pressure only gradually as it rises through the seal leg 14.

From the above it is seen that operation according to the invention provides a uniform flow of solids downwardly through the seal leg and a uniform flow of sealing steam upwardly through the seal leg and thus minimizes or eliminates any tendency for nonuniform conditions to interfere with or stop the flow of catalyst through the seal leg.

Although the invention has been described with reference to a hydrocarbon conversion catalyst, it is to be understood that it is also applicable to inert, porous, contact material of the known types used in hydrocarbon conversion processes.

The invention claimed is:

1. In a process for conversion of hydrocarbons which comprises introducing porous granular hydrocarbon conversion supporting contact material unsaturated with steam into a relatively expanded supply zone, gravitating contact material from said supply zone into and through an elongated relatively confined zone against gradually downwardly increasing pressure, gravitating contact material from said confined zone into a sealing zone, introducing contact material from said sealing zone into a conversion zone, and contacting hydrocarbons with said contact material in said conversion zone under conversion conditions, the improvement which comprises: introducing steam into said supply zone to substantially saturate said contact material with steam at the pressure in said supply zone; introducing additional steam into said confined zone to further increase the adsorbed steam content of said contact material, substantially all of the contact material which is contacted with said additional steam being subsequently introduced into said sealing zone; introducing steam into said sealing zone; and passing steam upwardly from said sealing zone into and through said confined zone.
2. Method according to claim 1 wherein additional steam is introduced at a level approximately equidistant between the adjacent upper and lower levels of steam introduction.
3. Method according to claim 1 wherein additional steam is introduced at a plurality of levels intermediate the ends of said confined zone.
